UNITED STATES PATENT OFFICE.

LEON U. SNOW, OF LINCOLN, NEBRASKA.

BLOW-TORCH.

1,296,869.

Specification of Letters Patent. Patented Mar. 11, 1919.

Application filed March 12, 1918. Serial No. 322,160.

To all whom it may concern:

Be it known that I, LEON U. Snow, a citizen of the United States, residing at Lincoln, in the county of Lancaster and 5 State of Nebraska, have invented certain new and useful Improvements in Blow-Torches; and I do declare the following to be a full, clear, and exact description of the invention, such as will enable others skilled 10 in the art to which it appertains to make and use the same.

This invention relates to blow-torches, and it relates more particularly to certain improvements in the arrangement and adjustment of a flame-producing wick and a 15 blast producing device.

One of the objects of this invention is to provide a device of this character which automatically generates the pressure for 20 producing the blast.

Another object is to provide for varying the pressure according to the attendant circumstances and requirements.

Another object is to provide for maintaining substantially an equal pressure in spite of the change in depth of the hydro-carbon employed for generating the flame and blast.

Another object is to provide a device of 25 this character in which the blast-producing device may be moved into and out of operative relation with the flame-producing device at will of the user.

Another object is to provide a device of 30 this character with a large scope of adjustments.

Another object is to provide a device of 35 this character which is compact and therefore convenient for transportation, storage 40 and operation.

Another object is to provide a device of this character which will not burn the hands of the user either during operation or adjustment.

Another object is to provide a device of 45 this character consisting of few and similar parts, so that the cost of manufacture and upkeep is reduced to the minimum.

Other objects and advantages may be 50 come apparent to persons who read the following details of description in connection with the accompanying drawings, in which:

Fig. 1 is a perspective view of my improved blow-torch.

Fig. 2 is a vertical, or longitudinal, sectional view of the same.

Fig. 3 is a transverse, horizontal, sectional view along the line of 3—3 of Fig. 2.

Referring to these drawings in detail, in which similar reference characters correspond with similar parts throughout the several views, the body portion of the device consists of an integral structure, generally indicated by the numeral 5, and comprising a major or relatively large container 6 and a minor relatively small container 7. The top 8 of the body 5 forms a cover for both the major and minor containers, and is provided with a threaded aperture 9 and a second threaded aperture 10, and in these apertures are secured threaded adjusting sleeves 11 and 12, respectively. The wick-tube 13 may be either movably or immovably held within the threaded sleeve 11, this tube being provided with a vent 14, which extends from the interior to the exterior of the hydro-carbon container 6. A wick 15 is held within and adjustable by the tube 13; it being understood that this tube may be adjusted either by the adjustment of the sleeve 11, or by its longitudinal movement within the sleeve 11. Any suitable locking means 16 may be employed for securing the sleeves 11 and 12 in adjusted positions.

The adjustable sleeve 12 receives a wick-tube 17, the latter extending into the minor container through the sleeve 12, and having its outer or upper end curved and provided with screw threads 18 which engage with a jet-cap or nozzle 19, a jet 20 of which is normally in vertical or longitudinal alinement with the longitudinal central line of the wick-tube 13. However, the tube 17 is rotatable within the sleeve 12, so as to bring the jet into and out of its operative relation with the wick 15. The main object of this rotary adjustment is to allow free access to the wick 15, and the tube 13 for the application and removal of a cover 21 which is shown in dotted lines in Fig. 2. This cover is useful for extinguishing the flame of the wick 15, and for preventing leakage of the hydro-carbon through the wick-tube 13 when the blow-torch is being transported to and from its work.

Because of the comparatively high pressure which is generated within the minor container, the wick-tube 17 is provided with a collar 22 extending therearound and fixed thereto. Any suitable packing material 23 may be disposed between the collar 22 and the sleeve 12, and a packing cap 24 co-oper-

ates with the collar 22 for preventing longitudinal movement of the tube 17 with relation to the sleeve 12. Moreover, this cap 23 may be employed for adjusting the sleeve 12 within the aperture 10 when the adjacent lock-nut 16 has been loosened, and this nut may be tightened for holding the sleeve 12 in its adjusted position.

From the foregoing, it will be seen that 10 a wide range of adjustment may be had by adjusting either or both of the wick-tubes within the sleeves 11 and 12, or by means of the sleeves.

The jet cap 19 and wick-tube 17 may be of 15 a metal having a relatively high heat conductivity, so that the heat generated by the wick 13 and applied to the elements 17 and 19 is conducted to the hydro-carbon in a wick 25 and in the container 7. Obviously, 20 such heating of the hydro-carbon causes it to vaporize and pass through the jet-opening 20. This jet-opening, however, is so small that the vapor accumulates under high pressure within the container 7 and tube 17, 25 and passes with considerable force and velocity through the jet-opening 20 in which the flame is generated by the wick 2, and this blast not only directs the flame to the point desired, but also adds fuel thereto.

30 The sleeve 12 and cap 23 are preferably formed of material having a low heat conductivity, so that when the cap 23 is employed as means for adjusting the tube 17, the fingers of the user will not be burned 35 thereby.

In operating the device, as the hydro-carbon becomes less deep within the container, the change in depth of the hydro-carbon will change the amount of pressure in the 40 container 7, and such change may be compensated for by lowering the tube 17 into the minor hydro-carbon container, or into the hydro-carbon contained therein, and the wick-tube 18 may be adjusted accordingly.

45 From the foregoing, it will be seen that I have provided a device of this character which is thoroughly practical and fully capable of effecting the foregoing objects, and because of the advantages obtained by 50 this construction and arrangement of parts, this device is meeting with very considerable commercial success.

Although I have described this embodiment of my invention very minutely, it is 55 to be understood that this invention is not limited to these exact details of construction and arrangement of parts, but that I am entitled to make such changes as do not constitute a departure from the inventive ideas 60 disclosed in the foregoing description and following claims:

What I claim as my invention is:

1. A blow-torch comprising a relatively long and narrow liquid fuel container having closed ends one of which is provided

with two apertures, a wick, a tube extending through one of said apertures and containing said wick, a second liquid fuel container in open communication with the other one of said apertures, a second wick, 70 a second tube, and a jet-cap on said second tube, said second tube containing said second wick and having one end in said second container and having its other end normally extending to a point substantially in alinement with the longitudinal central line of the first said tube. 75

2. A blow-torch comprising a relatively long and narrow liquid fuel container having closed ends one of which is provided 80 with two apertures, a wick, a tube extending through one of said apertures and containing said wick, a second liquid fuel container in open communication with the other one of said apertures, a second wick, a second tube, and a jet cap on said second tube, said second tube containing said second wick and having one end in said second container and having its outer end portion curved so as to normally extend to a point in 85 alinement with the outer longitudinal central line of the first said tube, said second tube being turnable to a position in which its outer end is out of said alinement relative to the first said tube. 90

3. A blow-torch comprising a relatively long and narrow liquid fuel container having closed ends, one of which is provided with two apertures, a wick, a tube extending through one of said apertures and containing said wick, a second liquid fuel container in open communication with the other one of said apertures, a second wick, a second tube, said second tube containing said second wick and having one end in said second container and having its outer end curved 100 and provided with a jet-opening normally in alinement with the length of the first said tube, the major part of the second said tube being substantially parallel with the first said tube, and means for effecting adjustment of one of said tubes with relation to the other said tubes. 110

4. A blow-torch comprising a liquid fuel container, a wick, means for holding and adjusting said wick in said container, a second liquid fuel container secured to the first said container, a second wick, and means for holding said second wick in said second container and for coöperating with both of 115 said wicks in creating a blast for blowing said wicks in creating a blast for blowing flame arising from the first said wick, the last said means being operable to move out of coöperative relation to the first said means so as to allow free access to the first 120 said wick for covering the latter. 125

5. In combination, an integral structure comprising a major container and a minor container, each provided with a threaded aperture, a threaded sleeve adjustable 130

in the aperture of the major container, a tube extending through said sleeve into the major container, a wick in said tube, a threaded sleeve having its threads adjustably engaged with the threads of said aperture of the minor container, a tube having a collar fixed thereon, a nozzle in the last said tube, a wick in the last said tube, and means coöperative with said collar and with the last said sleeve for effecting adjustment of said nozzle with relation to the first said wick.

6. In combination, an integral structure comprising a major container and a minor container, each provided with a threaded aperture, a threaded sleeve adjustable in the aperture of the major container, a tube extending through said sleeve into the major

container, a wick in said tube, a threaded sleeve having its threads adjustably engaged with the threads of said aperture of the minor container, a tube having a collar fixed thereon, a nozzle on the last said tube, a wick in the last said tube, and combined packing and adjusting means coöperative with said collar and with the last said sleeve for effecting adjustment of said nozzle with relation to the first said wick.

In testimony whereof I have hereunto set my hand in the presence of two subscribing witnesses.
